UMBRELLA ANCHOR

Dietrich Wiegmann, Bremen, Germany, assignor of one-half to Paul Tobeler, doing business as Trans-Oceanic, Los Angeles, Calif.

Application March 24, 1955, Serial No. 496,548

6 Claims. (Cl. 189—92)

This invention relates generally to subterranean anchors for supporting walls, piles and the like, and more specifically has to do with umbrella anchors having arms adapted to be expanded underground to provide tension or bearing supports for corresponding loads. The invention especially concerns itself with a novel type anchor adapted to be introduced underground in a casing and subsequently manipulated from a remote point after removal of the casing to accomplish expansion of the anchor arms into the surrounding subterranean material.

In previous devices of this sort, the anchor arms have in certain cases been connected to supporting structure in such a way that expansion of the arms was sought to be accomplished by displacing the support structure with cement or other material introduced in the hole, the weight of the cement being depended upon to expand the arms outward into the soil. In other cases the protective casing was left in the ground and the anchor arms were forced out through slits in the casing by interengagement between the arms and shoulders on the casings when the supporting structure was displaced.

Disadvantages inherent in such devices have to do with uncertainty of spreading of the anchor arms, and the difficulty of causing penetration of the arms into the soil. Similarly, in those devices wherein the arms are exposed to the soil during driving of the casing, the adherence and compaction of dirt to the arms contribute to the uncertainty and difficulty of securing desired expansion of the anchor assembly.

The present invention obviates these problems, assuring positive expansion of the anchor assembly, to provide desired footing, and furthermore contemplates the provision of readily expandable anchors capable of withstanding tension or compression loading. Furthermore, by virtue of the essential simplicity of the device, it is readily possible to construct additional anchorages for supporting walls or the like in front of or adjacent to existing construction facilities which are already weighed down, so as to lend additional support to such facilities or to provide additional anchorages for extension of such facilities.

In accordance with the invention, there is provided an umbrella anchor assembly including anchor arms carried at the lower end of a shank, which is movable axially inside a protective casing and manipulatable from the surface above the upper end of the casing. The arms are positioned circumferentially around the shank and pivotally connected to a pair of collars in such a way that after the casing is removed, one collar may be forcefully moved toward the other, causing the arms to expand outward and away from the shank for engagement with and penetration into the adjacent soil to form the desired footing. To this end, one collar is fixed on the end of the shank and the other collar is spaced therefrom and slidably mounted on the shank for manipulation from the surface by means of a sleeve or tube surrounding the shank. Forceful displacement of the sleeve against the movable collar and toward the fixed collar causes posi-

2

tive spreading of the anchor arms into the adjacent soil, without the aid of such materials as concrete poured on top of the anchor.

Other features and objects of the invention include 5 hinging the arms to either the fixed or movable collar to provide in one case a tension anchor and in the other a bearing anchor, as will be explained in detail. Closing movement of the two collars is advantageously limited by a shoulder carried by the shank between the collars to prevent over-expansion of the arms of the anchor. Each of the arms carries lateral surfaces which face and curve away from the shank, so that when the arms are spread they will move outwardly to penetrate the earth along a path of least resistance, thereby minimizing the power required to accomplish anchor expansion. The arms are desirably formed in T-section to facilitate direct penetration into the soil, and also to provide strength and rigidity.

Additional features and objects of the invention, as 10 well as the details of an illustrative embodiment thereof, will be more fully understood from the following detailed description of the accompanying drawings, in which:

Fig. 1 is a sectional view of the protective casing illustrating the collapsed condition of the umbrella anchor therein;

Fig. 2 is an elevation illustrating the umbrella anchor in opened or spread position after removal of the casing;

Fig. 3 is an end view of the umbrella anchor in spread position;

Fig. 4 is an end view, partly in section, showing the position of the umbrella anchor in collapsed condition within the casing;

Fig. 5 is an enlarged sectional view taken on line 5—5 of Fig. 3;

Fig. 6 is a view similar to Fig. 1 showing a modified form of the apparatus; and

Fig. 7 is a view similar to Fig. 2 showing the spread position of the modified anchoring apparatus.

Referring to Figs. 1 through 5, the expandable anchor assembly 10 is mounted on an end portion of anchor shank 11, which is extensible through the cylindrical protective casing 12 having an open end 13 facilitating withdrawal of the casing from the anchor assembly 10 through the open end. Anchor shank 11 carries a pair of collars 14 and 15, the former being retained in fixed position on the threaded end of the anchor shank between nuts 16, and the latter being slidable on shank 11 toward and away from collar 14. A sleeve 17 is interposed between the two collars and mounted on shank 11 to limit the movement of collar 15 toward collar 14 for purposes to be explained.

A series of brackets 18 are fixed on the side of collar 14 facing collar 15 for supporting the ends of anchor arms 19 from hinge connections such as pins 20, the anchor arms being positioned symmetrically around shank 11 and extending in the direction of shank 11 when in collapsed condition as shown in Fig. 1. Each 50 of the arms 19 is formed to have a T-shape in cross-section, including a longitudinally curved base 21 and a central web 22, a section of which is divided into laterally spaced portions 23 resulting in a double-webbed T construction as shown in Fig. 3. The base is slotted beneath the elongated opening 24 formed between web portions 23 to receive a push rod or lever 25, one end of which is hinged between web portions 23 and the other end of which is hinged to slidable collar 15, the hinge connections being suitably formed by pins 26 and 27.

The base 21 of each of the arms comprises a spade-like surface, which is convex toward shank 11 and which extends from bracket 18 toward the free end of arm 19

with an ever widening lateral dimension, as better shown in Fig. 3. The widened outer end 28 of each of the bases is sharpened at its forward edge to facilitate penetration into the earth, as will be explained.

In operation, the anchor arm assembly 10 mounted on anchor shank 11 is introduced into the drill casing 12, which extends into a formation beneath the earth surface. When in collapsed condition, the anchor arm assembly slides freely through the casing, since the arms 19 are mounted by brackets 18 in such a way that the arms pivot inwardly out of engagement with the inner walls of the casing, forming a clearance therebetween. After the assembly has been introduced to the bottom of the casing, the latter is removed a short distance, as by pulling it upward, so that the anchor arm assembly passes through the end portion 13 of the casing and becomes exposed to the earth at the bottom of the drilled hole. The assembly is then spread open in umbrella-like fashion by forcing collar 15 toward collar 14, as by means of sleeve 29. The latter slides over anchor shank 11 into direct engagement with collar 15 and is caused to force the latter collar toward collar 14 to open the anchor arm assembly, suitable retaining forces being exerted in an opposite direction on anchor shank 11.

Closing movement of the two collars urges push-levers 25 toward fixed collar 14 and causes the hinge connection at 26 to force the anchor arms outward and away from the anchor shank, the arms pivoting about pins 20. Resistance to penetration by arms 19 may be overcome by exerting sufficient equal and opposite forces on sleeve 29 and anchor shank 11, as by means of a hydraulic press operable at the surface of the earth. Anchor arms 19 are thereby spread open to approach a 90° angle with respect to shank 11, as shown in Fig. 2, over-spreading of the arms being prevented by engagement of collar 15 with the end of sleeve 17. It will be apparent that relative displacement between portions of sleeve 29 and shank 11 at the earth surface serves to inform the operator of the extent and condition of arm spreading.

Once the anchor has been brought into desired spread condition, push-sleeve 29 is removed and casing 12 is pulled upward from the earth, the hollow space left by the casing then being filled with sand or other material, along with added water, to eliminate any hollow spaces in the earth surrounding the anchor. Alternatively, concrete may be pulled into the opening to fill the voids left by removal of the casing.

Forming the bases 21 of the anchor arms to have a convex shape enables their penetration into the formation surrounding the anchor with minimum resistance, since enlarging of the penetration openings caused by their displacement into the earth is thereby kept to a minimum. During spreading of the arms into the earth, the anchor collar 14 is slightly shifted in the direction of pulling upon anchor shank 11; however, after spreading is completed, further displacement of the anchor is not possible since the bases 21 of the arms flatly engage a large portion of the earth immediately surrounding the anchor, resistance to displacement of which is transmitted to movable collar 15 abutting sleeve 17 and preventing movement thereof. For this reason, the present device serves very effectively as a tension-resisting anchor.

In the construction shown in Figs. 6 and 7, the position of anchor arms 19 and push levers 25 is reversed, the arms being hinged to movable collar 15 and the push levers hinged to the fixed collar 14. In addition, the anchor shank 11 comprises end sections 11a and 11b threaded together in end-to-end relation, and the threaded connection 30 between sections 11a and 11b may be rotated to disconnect it from section 11a for removal from the drilled hole.

When the anchor arms are spread by forcing movable collar 15 toward fixed collar 14, the spade-like bases 21 of the arms facing the lower or threaded end of the

anchor shank spread away therefrom, adapting the anchor assembly to be used as a support capable of withstanding compression loading such as may be exerted by pilings, columns and the like. Removal of the casing 12 and concreting of the empty hole left thereby remain the same as previously described. In addition, it is possible to use a pull cable permanently fixed to section 11a instead of utilizing anchor shank 11b.

I claim:

1. The combination, comprising an elongated tubular casing adapted to be inserted into a hole drilled underground, an expansible anchor assembly within the casing and adapted to be expanded after endwise removal of the casing so as to expose the anchor assembly to the surrounding underground formation, said assembly including an elongated anchor rod axially movable within the casing to carry said assembly underground and manipulatable from the surface of the earth, a plurality of elongated anchor arms circularly spaced about the end portion of said rod and extending substantially longitudinally therewith in collapsed condition accommodating free axial movement of the entire assembly within the casing, fixed and movable supports carried in axially spaced relation on the rod near the end thereof, and means including links and pivots relatively loosely interconnecting one end and the intermediate portion of each arm respectively to said supports, each of said arms being substantially longer than the diameter of said casing and including an elongated relatively narrow blade extending in a longitudinally curved plane that is everywhere convex toward the anchor rod, each blade diverging from a location adjacent the rod to the free end of the blade adjacent the inner wall of the casing, the free ends of the blades being sharpened and having transversely curved relatively widened extent, each of said arms also including web means integral with said blade and extending longitudinally at the blade outer side facing said casing, said pivots being connected to said links, webs and one of said supports and said blades containing longitudinally elongated openings through which said links project, and means for displacing said movable support relatively toward said fixed support for causing the links to swing the arms outwardly about their pivoted ends and away from said rod.
2. The invention as defined in claim 1 in which said supports comprise collars one of which is attached to the rod near the end thereof and the other of which is axially slidable on the rod.
3. The invention as defined in claim 2 in which said one end of each arm is pivotally connected to the collar attached to said rod.
4. The invention as defined in claim 2 in which said one end of each arm is pivotally connected to the collar slidable on the rod.
5. The invention as defined in claim 2 including a stop sleeve on the rod between the collars to stop relative closing together movement of the collars when said arms have been swung outward to extend substantially normal to the rod, and in which said means for displacing the movable collar comprises an elongated sleeve on the rod at the side of the movable collar opposite said stop sleeve.
6. The invention as defined in claim 5 in which said web means includes a pair of webs integral with each blade, each of said links extending between a pair of webs and being pivotally connected thereto.
